CLAIM

The ornamental design for a portable storage container, as shown and described.

DESCRIPTION

FIG. 1 is a top perspective view of a portable storage container showing our new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines in the figures are for the purpose of illustrating portions of the portable storage container and form no part of the claimed. design.
